United States Patent Office.

ABRAHAM W. OVERBAUGH, OF NEW YORK, N. Y.

Letters Patent No. 64,899, dated May 21, 1867; antedated May 16, 1867.

PORTABLE BLACKING-CASE.

The Schedule referred to in these Letters Patent and making part of the same.

TO ALL WHOM IT MAY CONCERN:

Be it known that I, ABRAHAM W. OVERBAUGH, of the city, county, and State of New York, have invented a new and improved Portable Blacking-Case; and I do hereby declare that the following is a full and exact description thereof, reference being had to the accompanying drawings, and to the letters of reference marked thereon.

Figure 1 is a perspective view of the case when opened and in position for use as a foot-stand.

Figure C represents a foot-rest, which consists of a piece of metal or other substance, made with a joint or hinge at each end, which, when inserted in the incisions in the case, forms a rest for the foot.

Figure D is a circular incision in the case in which the box of blacking is to be inserted, and is retained in its position by a slide, A, which, by means of a thumb-screw, B, can be made to retain either a large or a small box.

Figure E is an incision in case to admit blacking-brush.

Figure F is an incision in case to admit polishing-brush.

Figure G is an incision in case in which the foot-rest C, when not in use and folded up at the joints, is to be placed.

Figure H is the foot at one end of the case.

Figure 2 is a view of the foot-rest, showing the foot-rest C when opened at the joint, and also when closed.

Figure 1 is a perspective view of case when open and in position for use as a bench.

Figure 3 is a view of case when closed, showing the position of feet 'h' when closed.

Figure 4 is a front view of case when opened.

The nature of my invention consists in the arrangement of blacking and polishing implements in the form of a book or box.

1. I claim the arrangement and combination of blacking and polishing utensils in the manner described, so that the case when unfolded forms a stand or bench.

2. I also claim the feet combined with the devices in the manner described, so as to form an even surface when closed.

ABRAHAM W. OVERBAUGH.
